United States Patent Office

Des. 202,020

Patented Aug. 17, 1965

202,020

PLACE MAT OR THE LIKE

Vera Way Marghab, 250 W. 57th St., New York 19, N.Y.

Filed Jan. 8, 1964, Ser. No. 78,131

Term of patent 14 years

(Cl. D92—26)

The single figure is a plan view of a place mat incorporating the design of the invention; the place mat is of conventional thickness.

I claim:

The ornamental design for a place mat, or the like, substantially as shown and described.
